UNITED STATES PATENT OFFICE.

EDWARD E. ROEWADE, OF CHICAGO, ILLINOIS, ASSIGNOR TO WRIGHT & DITSON-VICTOR CO., OF NEW YORK, N. Y., A CORPORATION OF MASSACHUSETTS.

FOOTBALL SHOE.

Application filed October 25, 1926. Serial No. 143,830.

This invention relates to football shoes and is especially concerned with a shoe adapted to be used by kickers.

Shoes designed especially for drop and placement kicking having a hard toe "box" or reinforcement, the end face of both the upper and the sole being square and sometimes merging so that a flat upright face is presented for contact with the football. In such a shoe the toe box or stiffener is molded to approximately the desired shape, the toe is relatively high, and the end and top faces of the toe merge on a prominent rounded line or edge. It is very difficult to punt with such a shoe since the rounded toe tends strongly to deflect the ball unless the foot and ball meet in just the right relationship. Punters, therefore, prefer the ordinary football shoe which, although made with a box toe, does not have the peculiar shape of a kicker's shoe.

The present invention aims to devise a superior shoe for punting and one which, at the same time, will be fully as useful for drop and placement kicking as the prior shoes designed especially for this purpose. While the invention is especially concerned with the requirements of a kicking shoe, it also aims to provide a shoe which will be suited to general football requirements and can be worn satisfactorily by both the backs and the linemen.

The nature of the invention will be readily understood from the following description when read in connection with the accompanying drawings, and the novel features will be particularly pointed out in the appended claims.

In the accompanying drawings,

Figure 1 is a perspective view of a shoe constructed in accordance with this invention;

Fig. 2 is a front view of the toe portion of the shoe shown in Fig 1; and

Fig. 3 is a longitudinal, vertical, cross-section through the toe portion of the shoe shown in Figs. 1 and 2.

According to the usual method of punting the top of the toe, and perhaps a part of the instep, come in contact first with the football, the foot then swinging inwardly and upwardly past the ball and thus imparting to it the desired twist or "spiral" motion. I have found that, contrary to what might be expected, punters can obtain far

better direction and control of a punt, and also better average distance, with a soft toed shoe than with a toe having the usual hard box. Such a shoe, however, as ordinarily constructed, would be unsuited for drop or placement kicking, the toe only of the shoe striking the ball in making either of these kicks.

Referring to the drawings, it will be seen that the shoe there shown is of the welt type and comprises an insole 2, vamp 3, welt 4, and outsole 5. The welt, insole and vamp are secured together by the usual inseam 6, while the outsole and welt are united by an outseam 7. The top of the toe portion of this shoe is devoid of a stiffener, and therefore is "soft." In order to facilitate the kicking of field goals a stiffener 8, Fig. 3, is used at the forward end of the toe, this stiffener, however, being very narrow so that its upper edge terminates approximately at the curve of the toe. This stiffener lies between the toe portion of the vamp 3 and a cap 9 which is secured to the vamp. The shoe shown is for a left foot and it will be observed that the rearward edge of the cap 9 extends from approximately the inner corner of the top, across the vamp, to a point in the shank at the outer edge of the shoe. In a right shoe the rearward edge of the cap would be inclined in the opposite direction but would bear the same general relationship to the inner and outer edges of the shoe.

The toe portion of the sole is square, and the toe portion of the upper conforms in outline to the end of the sole. This part of the upper, however, is so shaped and the reinforcement 8 is so molded, that the toe portion of the upper presents a broad flat face for contact with a football, the end of the toe being approximately in line with the flat face of the square toed sole. In other words, the toe of the shoe is squared both vertically and horizontally so that it presents the broad blunt face which is desirable for either drop or placement kicking.

Experience has demonstrated that this shoe is fully as satisfactory for either drop or placement kicking as the hard molded box toes heretofore used. The fact that the upper part of the toe of the shoe is soft and devoid of a hard stiffener makes the shoe decidedly superior to former constructions for punting. The reason appears to be that the soft toe enables the player to get a certain

"feel" of the ball which is impossible in a shoe having a hard box toe. The player therefore can acquire with a reasonable amount of practice the ability to guide and 5 direct the ball more accurately than otherwise would be possible.

When the upper of the shoe is made of the stock ordinarily used in football shoes, usually kangaroo, there is a strong tendency 10 for the upper leather to wrinkle badly over the outer side of the foot, but this tendency is effectively overcome by using the cap 9 which preferably is made of the same material as the upper.

15 Because of the difficulty in punting and kicking field goals with the same shoe, it has usually been customary not to call on the punter for drop or placement kicks, and this fact often has been a handicap both in planning the strategy of a game and also in the execution of the plays. That it, if a single 20 player can be relied upon either to kick field goals or to punt, he carries an additional "threat" which is valuable. If two or more 25 backs have this same ability, then the threat is increased and their usefulness in the strategy of the game is enhanced. The fact that the shoe provided by this invention facilitates drop and placement kicking as well as 30 punting is, therefore, an important practical advantage in the game. An additional advantage resides in the fact that the punter both can control the direction of the ball

more accurately and can also feel more confidence in giving to the ball the twist or 35 spiral motion which is effective in securing greater distance.

While I have illustrated a shoe of the welt type, it will be understood that the invention can be embodied in other makes of shoes, as 40 for example, the McKay type. The invention, therefore, is not limited to the exact details of the construction shown.

Having thus described my invention, what I desire to claim as new is:

1. A kicking shoe having a square toed sole, a stiffener reinforcing the upper at the end only of the toe, the top of the toe portion of the shoe being soft, said reinforced end of the toe portion of the upper following the contour of the toe part of the sole, and a cap covering the portions of the upper at the toe and the outer side of the foot substantially to the shank.

2. A kicking shoe having a square toe, a 55 stiffener reinforcing the end portion only of the upper of the shoe at the toe, the top of the toe portion of the shoe being soft and unstiffened, and a cap covering the toe and a portion of the vamp along the outer side of 60 the shoe, the rearward edge of said cap extending from approximately the inner toe corner, across the vamp, to the shank at the outer edge of the shoe.

EDWARD E. ROEWADE.
